ELECTRIC HEATER, RECESS TYPE

Julien A. Bried, Oakland, Calif.

Application August 16, 1927. Serial No. 213,384

7 Claims. (Cl. 219—34)

This invention relates to electric heaters as mounted in the walls of rooms and wherein the electric heating element of whichever type used is usually entirely or substantially within a recess formed in the wall so that the heat generated is available at the open front of the recess usually covered by a grille.

In all wall electric heaters of this recess type where any amount of heat is generated it is necessary that the recess in the wall be relatively large in proportion to the size of the heating element positioned therein and that in case of inflammable walls the recess be lined with metal and provided with one or more spaced rear plates so as to form open air spaces, especially at the rear of the heating element, and which spaces are in effect flues for the upward and forward discharge of the air heated in the recess in back of the element, so as to keep the recess cool and also to obtain some useful heat from the rear of the element.

It is also customary to provide a protective grille or guard of wire over the open face of the recess to prevent danger of personal contact with the hot element.

Further, in order to keep the recess as cool as possible, the electric heating elements are provided with heating coils on their front faces only, so as to keep the heat as much as possible on the front of the element for dissemination into the room to be heated.

Such electric heaters as described are well known in the art, and some of their objections are that they overheat the wall unless the special air flue arrangements as described, are resorted to and the recess is large, and insulated with asbestos or the like, also the usual 2 x 4 studding used in the wall of homes limits the depth of the wall recess so that the heating elements must necessarily be small to permit the required air flues in back of them, also since the grille is at all times open, a great quantity of dust and dirt accumulates within the heater and is very difficult to remove.

The objects of the present invention are to overcome the objections above noted, in permitting the use of a relatively large heating element with a shallow wall recess, dispensing entirely with the rear cooling flues, getting full advantage of the rear heated surface of whatever element is used, and providing a door or doors for tightly closing the recess, whereby the interior of the heater and element or elements are protected from injury and dust during the long

periods of non-use, usually many times greater than their periods of use.

Further objects are to provide means whereby it is impossible to energize the heating element unless the door which encloses the recess be wide open, still further that the opening of the door will actuate a switch so that the element is thereby energized, or may subsequently be energized by actuation of another switch. Another object is to provide means by which the heating element will be drawn out of the recess to stand in front of the wall of the room before energizing, so that all of the air which it heats may freely ascend in front of the wall, also means is provided to positively prevent energizing of the element before it is so withdrawn from the recess, also means by which the opening and closing of the door will respectively draw out and return the element, from and to the recess. Other objects will appear in the following specification.

In the drawing hereto, several variations in mechanism for accomplishing the above objects are shown.

Fig. 1 is a horizontal section of a wall recess with two electric heating elements enclosed therein by a pair of doors, all as seen from the line 1—1 of Fig. 2. Fig. 2 is an elevation of Fig. 1.

Fig. 3 is an enlarged sectional elevation of one of the elements showing the adjacent supporting structure and grille. Fig. 4 is a sectional plan view of the wall recess and casing showing a manual switch arrangement operable only when the doors are open. Fig. 5 is a similar view to Fig. 4 showing switches operatively hooked up to the doors. Fig. 6 is a similar view to Figs. 4 and 5 but shows the doors closed and a single manually operable switch which is inoperative unless both doors are wide open. Figs. 7 and 8 are sectional diagrammatic views of a wall recess showing a variation in the manner of withdrawing the heating element by the opening of the doors.

In the illustration I show the use of a vertical hollow tubular electric heating element 25 so that heated air may readily pass up through it. Such elements have been known and used for a long time in electric heaters, some had the resistance or heating coils wound on a short section of clay pipe, or on insulated metal pipes, or just in the form of suspended coils. There are many types in the art and any of them are adaptable to the present invention, and while I prefer the hollow flue type of element it should be noted that the other forms of electric heating elements such as the flat plate type, bulb type,

or any other, may be employed to certain advantage in connection with my invention if desired, as it is not limited to the use of the vertical hollow flue type of element, tho it gains additional advantages with the flue type.

Also, since the specific construction of the element is apart from the invention no attempt at detailing this is made in the drawing.

In the drawing the room wall is designated 10 and the recess 2. Within the recess is fitted a sheet metal box 3 as is common to all such construction so as to finish the inside of the recess, and at the outer edge of the lining is a frame 4 adapted to be screwed to the outer face of the wall 15 and to which frame is pivotally mounted a pair of sheet metal doors 5 which close tightly as shown in Fig. 1 or swing open substantially parallel with the wall until stopped by the frame as 20 shown in dotted position. The doors are preferably curved slightly and are carried on and secured to substantial pivot rods 6 so that the rods must turn with the doors. To effect this the rods may be pinned to the door lugs, or squared or keyed where they pass through, or in any other well known manner. The lower end of each pivot rod projects into a base extension 7 of the frame forming a switch and wiring box beneath the bottom 3' of the recess lining, and each rod is 25 directly connected to and operates a snap switch 8 of any suitable and well known construction not detailed.

The switches 8 are so set that they operate to close the heating circuit just as soon as the doors are wide open, and to open or break the circuit 30 when the doors are given a short movement in a closing direction, hence upon opening either door wide its switch will close a circuit and upon a slight closing of either door the circuit will be broken.

It is contemplated that the energizing circuit for the heating element or elements pass through both these switches so that if either door is not fully open the circuit will be broken and the heater cannot be energized, and when the doors are both open the heater will be automatically energized. Or if desired, each door switch may be on one only of the elements so that the opening of one door brings out and energizes one element and the other door the other element.

Also it is contemplated that a further switch 9 may be on the circuit to control in the usual manner any degree of heating of the elements by switching in any amount of their heating coils, further, that this switch 9 be a manually operated switch closed in by the doors when they are closed so as to be inaccessible except when the doors are open, also that this switch 9 be of a type with an arcuate lever handle 9' or other projection adapted to get in the way of the doors 35 when this switch is closed (to either of the dotted positions A, B) so that a further safeguard is provided against closing the doors with the heat turned on. In fact, with the arrangement described the circuit must be broken in three places; if switch 9 is used; before the doors can be closed.

The heating elements in Figs. 1 to 3 comprise two vertical tubular supports 25 wound with resistance wire, each support swingingly mounted on arms 10, 11 freely embracing the door pivot rods 6 so that the elements can swing into the recess as shown in full lines in Fig. 1, or out of it as indicated by the dotted position of the elements. The doors or rods are equipped with suitable lugs or links, one form being shown at 12, so as 40 to engage the arms to give them the required

amount of movement upon opening or closing of the doors, as the arms only move through about half the arc that the doors do. Suitable stops (not shown) are provided to limit the outward movement of the elements.

The hollow elements are entirely open on bottom and top so that when out of the recess and energized the heated air may freely ascend through the elements, and they are protected with a light wire grille 13 which permits free ascension of heated air all around the outsides of the elements.

Thus when the elements are out of the recess and energized, the heated air is free to ascend through and around the elements in front of the wall of the room, and no rear baffle plates or air flues are required to protect the recess from over-heating as the heated elements are not within it, but are out in the open.

If desired, a very light ribbed, crinkled, or indented and polished copper sub-lining may be placed within the recess as at 14 to give a more pleasing background for the dull glow of the heating coils on the elements, and the effect of fire may be further enhanced by means of a 100 supplementary small electric lamp at 15 energized from the heating circuit and shaded by a reflector 15' so as to shine upon the undulatory or crinkled polished sub-lining.

In Fig. 3 the mounting of the tubular elements 25 between upper and lower arms 10 and 11 is clearly shown. The arms terminate in spiders provided with lugs 26 to center the element, while a central rod 27 firmly screwed into the central boss of the lower arm 11 passes freely through the boss of the upper arm 10, and a castellated nut 28 screwed on the upper end of the rod locks both spiders against the ends of the element, care being used if the element is fragile that sufficient play be left to prevent breakage. The wire guard 115 or cage 13 surrounding the element is also spaced by the arms, vertical wires 13' of the cage being arranged to enter holes in the ends of the arms.

In Fig. 3 the resistance or heating coils are indicated at 29 as wound in grooves around a 320 refractory insulating tube or pipe, but as stated above, the coils may be variously wound on the support or imbedded if desired.

In Fig. 4 an arrangement of two manually operated snap switches 8' is shown, the switch 125 handles 16 being dotted in the "off" position and drawn in full lines lying with their ends against the open doors when in the "on" position with the circuit closed. Hence the switches cannot be operated unless the doors are open, and will snap off to position "C" when the doors are moved to bring the lever to position "D". Fig. 5 shows a similar arrangement to that of Fig. 4 except that the switch handles 17 are slidably connected to the doors at 18 so that they are positively operated by the doors.

Fig. 6 shows a manually operated switch at 19 only, but which has a pair of sliding rods 20 connected to it so that in turning the switch to the right to energize the elements, the doors must 140 first be open to clear the ends of the rods, and the switch must be turned to the left to withdraw the rods to the position shown in the figure before the doors can be closed.

In all the other switch arrangements except 145 that of Fig. 6 the energy of the snap switch springs tends to hold the doors in extreme open position.

In Figs. 7 and 8 a hollow element 25' is shown 150 which is forced substantially straight in and out

5	of the recess upon closing or opening of the doors, the door pivots 6' carry upper and lower arms as at 21, similar in action to arms 10 of Fig. 1, slidably engaging a frame 22 supporting the element or elements.	the recess when the element is within the same, and means preventing energizing of the element when same is within the recess.	
10	In the movement of the elements in and out of the recess a flexible electric cable (not shown) leading from the switch box space below the lower lining, extends to the elements through holes 23 in the lower lining plate 3' shown in Fig. 1, thus leading the energy from the switches and wiring space below.	4. An electric wall recess type room heater comprising an electric air heating element disposed within a wall recess, a door arranged for closing over the recess, and means preventing the energizing of said element except when said door is open, said door hingedly mounted so as to be in vertical position when open to thereby form no obstruction to the free ascent of air currents in front of said recess.	80
15	The switch and wiring space below the lining is accessible by having the lower plate 3' loose or removable.	5. In a wall-recess type electric air heater, an electric air heating element mounted for movement into and out of the recess whereby when in the latter position its heat will ascend upward in the room forward of the recess, and a guard spaced outward of said element movable in and out of the recess with the element, the space between the guard and the element being open at top and bottom so that air may freely ascend between the guard and the element.	90
20	Attention is called to the fact that while I have shown two elements and two doors in Figs. 1 and 2, it is understood that any number of elements or style of elements may be used, or but one element and one door, and that while I show a laterally opening hinged door, any other type of door opening in any direction may be used.	6. An electric air heater comprising an electric air heating element disposed within a wall recess, a door in front of the recess provided with means vertically pivoting the same for closing over the recess, means mounting said air heating element for swinging out of the recess when the door is opened, the arrangement being such that when the element is out of the recess the air to be heated may freely pass upward and around the element with substantially no obstruction.	95
25	Also, that while I show in Figs. 1 and 2 a door which operates the circuit switch, a switch which will operate the door is the same in some respects, as in the drawing the door and switch are mutually dependent, as the movement of operating the door may just as well be considered the movement of operating the switch, the door knobs 24 of Figs. 1 and 2 being equally the switch handles.	7. An electric air heater comprising an electric air heating element disposed within a wall recess, a door in front of the recess provided with means vertically pivoting the same for closing over the recess, means mounting said air heating element for swinging out of the recess when the door is opened, the arrangement being such that when the element is out of the recess the air to be heated may freely pass upward and around the element with substantially no obstruction.	100
30	I claim:—	120	
35	1. In a wall recess type of electric heater, a vertical hollow flue type electric heater mounted in the recess so as to move outwardly therefrom to permit its heat to ascend freely in front of the wall in which the heater is mounted.	125	
40	2. In a wall recess type of electric heater, a vertical hollow flue type electric heater mounted in the recess to move outwardly therefrom to permit its heat to ascend freely in front of the wall through said flue.	130	
45	3. In a wall recess type electric heater, an electric heater of the vertical flue type mounted so as to swing from a position within to a position without the recess, a door arranged to cover	135
